Patented July 6, 1971

221,081

RECTIFIER

Robert D. Kahn, Rockville Centre, N.Y., assignor to
Fedtro, Inc., Rockville Centre, N.Y.

Filed Aug. 18, 1969, Ser. No. 18,726

Term of patent 14 years

Int. Cl. D13—99, 02

U.S. Cl. D26—1

FIG. 1

FIG. 2

FIG. 3

FIG. 4

FIG. 5

FIG. 1 is a top perspective view showing the rectifier;
 FIG. 2 is a bottom perspective view thereof;
 FIG. 3 is a top plan view thereof;
 FIG. 4 is a bottom plan view thereof; and
 FIG. 5 is a side elevational view thereof, all side
 elevational views being essentially identical.

I claim:

The ornamental design for a rectifier, as shown and described.
